UNITED STATES PATENT OFFICE.

ROY EUGENE LOWEY, OF HUNTINGTON, INDIANA.

COLLAPSIBLE FRUIT BOX.

Application filed May 23, 1921. Serial No. 471,665.

To all whom it may concern:

Be it known that I, ROY EUGENE LOWEY, a citizen of the United States, residing at Huntington, in the county of Huntington, 5 and State of Indiana, have invented certain new and useful Improvements in Collapsible Fruit Boxes; and I do hereby declare the following to be a full, clear, and exact description of the invention, such as will 10 enable others skilled in the art to which it appertains to make and use the same.

My invention relates to improvements in collapsible boxes such as are used for small fruits or vegetables, or the like, such boxes 15 being preferably made of cardboard or other suitable collapsible material.

With such devices it is especially desirable to transport same from the maker to the vendor or to the user in the knock-down form for convenience in transportation and storage, and to have the devices so constructed that each unit shall constitute a complete box without the possibility 20 of any of the parts becoming detached or lost, and the box so arranged that it may be quickly set up in the proper position for use, or quickly knocked down again when desired.

With such devices it is especially important that the box shall be cheap and simple 30 in construction and efficient in use; also that it shall not require any special skill or intelligent manipulation, as such boxes are designed for use by unskilled labor, generally, often by children.

My invention will be more fully understood after reference to the accompanying drawings, in which like parts are indicated by similar reference symbols throughout the 40 several views, and in which:

Figure 1 is a perspective view of the box in the set-up position ready for use, parts being shown broken away for the sake of clearness in the drawings.

Figure 2 is a plan view of the box shown in Figure 1, but with part of the bottom broken away to show the supporting lips.

Figure 3 shows a section along the line 3—3 of Figs. 1 and 2, and looking in the 50 direction of the arrows, the bottom being shown in dotted lines in the raised position.

Figure 4 is a plan view of the box in the collapsed condition, the parts being 55 shown on a smaller scale.

Figure 5 is a plan view of the tongue used

to form the four sides of the box, the parts being on the same scale as in Figs. 1 to 3.

Figure 6 is a plan view of the blank which forms the bottom of the box; and 60

Figure 7 is a detail showing one of the staples the dotted lines indicating the same when in the bent over position.

A represents the main blank which forms the four sides of the box. This blank is 65 provided with creased or weakened lines 1, 2 and 3, to facilitate bending the blank to form the corners of the box. The blank is also provided with creased or weakened lines 4, 5, 6, 7 and 8 to provide for folding 70 the end lip 9 and the bottom supporting lips 10, 11, 12 and 13.

The blank A is also provided with a tongue 14 stamped out of one side thereof, and opposite the bottom hinge of the bottom, as will be hereinafter described, to serve as a latch to prevent the bottom from being lifted upwards accidentally or when not desired. 75

The blank B is provided with a creased or weakened line 15 adjacent to the lip 16, which lip is held between the lip 11 and the adjacent side of the box by means of a staple C, shown in Figs. 2 and 3. Such a staple is shown in detail in Figure 7. 80

In assembling the parts when in the knock-down condition the lips 10, 11, 12 and 13 are bent inwards and fastened to the adjacent inner wall of the blank A by staples C or C', all of said staples being of similar construction to that shown in Figure 7. 85

The lip 16 of the bottom blank is secured between the lip 11 and the adjacent side of the box opposite the tongue 14 when the box is in the open condition shown in Figure 1. 90

The end lip 9 of the blank A is secured to the opposite edge of the blank, preferably by glue or cement, but it may be also stapled to the same if desired.

When in the collapsed form the box lies 100 flat with the end of the bottom blank B projecting as shown in Figure 4. In order to open up the box and get it ready for use as a receptacle, all that is necessary is simply to spread open the opposite sides of the quadrilateral formed by the blank A, then swing down the bottom blank from the position shown in dotted lines in Fig. 3 to the position shown in full lines in Fig. 3, and then push in the tongue 14 which will serve as a 110 latch to prevent the free end of the bottom from swinging up.

Owing to the fact that the lips 10, 11, 12 and 13 are secured at their central portions by the staples, the free ends of these lips, due to the resiliency of the cardboard, will 5 tend to spring inwards when the box is opened up, assuming the position shown in Fig. 2 and thus forming a most efficient supporting shelf for the bottom of the box when the latter is filled with fruit or other 10 contents.

In order to knock-down the box it will be simply sufficient to press out the tongue 14, push the free end of the bottom B up to the position shown in dotted lines in Fig. 3 and 15 then collapse the sides of the box. The parts then return to the position shown in Fig. 4.

Thus it will be seen that the boxes as made may be shipped to the farm in the knock-down condition, may be filled with fruit, 20 and when sold may be either thrown away by the purchaser, or the boxes emptied of the contents and shipped back to the user in the knock-down condition.

It will thus be seen that I provide a very 25 cheap, durable and efficient container for the purpose stated which may be readily transported or re-transported in compact space

and quickly and conveniently set up for use, or knocked-down as may be desired.

It will be obvious that various modifications might be made in the herein described apparatus and in the construction, combination and arrangement of parts which could be used without departing from the spirit of my invention; and I do not mean to limit 30 the invention to such details except as particularly pointed out in the claim.

Having thus described my invention what I claim and desire to secure by Letters Patent of the United States is:—

A knock-down box formed of two foldable blanks provided with weakened folding lines, said blanks being connected together to form, respectively, the bottom and sides of the box, the blank for the sides being provided with a plurality of lips bent upwards from the bottom thereof, and the bottom blank being provided with a lip secured inside of one of the lips of the side blank, and the said side blank being provided opposite 45 said bottom lip with a tongue made integral therewith and adapted to be pressed inwards to form a latch for the bottom of the box.

ROY EUGENE LOWEY.
